HEAT SENSITIVE DEVICE

Benjamin Cyr, Minneapolis, Minn., assignor to
 Minneapolis-Honeywell Regulator Company,
 Minneapolis, Minn., a corporation of Delaware

Application July 5, 1941, Serial No. 401,200

15 Claims. (Cl. 200—137)

The present invention is directed to devices which are responsive to changes in temperature, and particularly double metal ribbon devices of the type disclosed in the copending application of Willis H. Gille, Serial No. 401,205, filed July 5, 1941.

One of the main objects of this invention is to design a device along the lines of the Gille device but with greater sensitivity to the appearance and disappearance of direct heat radiations. This is accomplished by adding slip friction in the connections so that the contact device is operated immediately upon a reversal in movement of the two legs of the double ribbon.

Another object is to design a double ribbon temperature responsive device in which the tension in the two legs may be readily equalized when the device is being assembled.

A still further object is to design a device of the above type in which the two legs are normally maintained under tension and which has a manual means for temporarily relieving the tension so that the ribbon may slip with respect to the support and bring the two legs to equal tension when tension is again applied to them.

These and other objects will readily become apparent as the following specification is read in the light of the accompanying drawing, in which:

Figure 1 is a side sectional view of a device involving my invention and taken along the line 1—1 of Figure 2;

Figure 2 is a rear elevation of the device, parts being shown in section for the sake of clarity;

Figure 3 is a detail view of the mounting lever;

Figure 4 is a side elevation of a modified form of my device, the lower portion being shown in section;

Figure 5 is a detail view of the roller on which the double ribbon of Figure 4 is supported;

Figure 6 is a detail view of the friction mounting for the roller shown in Figure 5;

Figure 7 is a side section of a third modification of my invention, and

Figure 8 discloses an oil burner for producing combustion within a furnace and one manner in which my device may be mounted in the wall of the furnace.

Referring now to Figure 1, the reference numeral 10 indicates a channel shaped supporting member having a pair of projections, one of which is shown at 11 in Figure 1, at one end thereof which are received in complementary depressions 12 in a mounting lever 13. By means of this arrangement the mounting lever 13 may

rotate about the projections 11. The mounting lever 13 is in the form of a U having a pair of legs 15 located on opposite sides of the supporting member 10.

5 A thin metallic strip in the form of a double ribbon indicated generally at 16 is supported across the base of the mounting lever 13 and a small projection 17 on the lever 13 extends through a small hole in the ribbon to prevent it from slipping with respect to the lever 13. The ribbon is bent double to form a pair of expandable legs 19 and 20 whose ends are bent into a channel shaped member 21. The ends are retained in this member by means of a clamping plate 22 and screw 23.

10 A resilient tensioning plate 24 is carried at each end by the channeled supporting member 10 and has an opening 25 in its middle portion through which a screw 26 loosely extends. The stem of the screw 26 enters a tapped hole in the member 21 and by rotating the screw 26 in a clockwise direction the member 21 may be drawn upwardly and the two legs 19 and 20 placed under tension.

15 Referring now to the sectioned portion of Figure 2, the reference numeral 28 indicates a cup-shaped member having an annular channeled portion which receives an annular graphite friction washer 29 which is adapted to bear 20 against the leg 15 of the lever 13. The cup 28 is provided with a center opening which receives screw 30 which in turn passes through the slot 32 in leg 15, which permits rotation of lever 13. Screw 30 enters a tapped hole 31 in the member 21.

25 A sleeve 32 surrounds the stem of the screw 30 and is of such length that when the screw 30 is tightened the cup 28 will bring the friction washer 29 into frictional engagement with the leg 15 of the lever 13 but will not clamp this lever against the support 10. In other words 30 the friction is due only to leg 15 bearing outwardly against the graphite washer 29. A mounting identical to the one just described is provided on the other leg 15 of the lever 13.

35 These two friction mountings resist the rotation of the lever 13 about the projection 11 but will permit such rotation upon the development of a predetermined force due to the differential expansion between the two legs 19 and 20. This 40 action will be described more in detail later.

An actuating rod 34 is provided with an enlarged head 35 having a slot 36 therein through which the two legs 19 and 20 are adapted to pass. These two legs are provided with small notches, 45 not shown, into which the edges of the slot 36

fit in order that the head 35 of the actuating rod 34 will be supported thereby. It will be noted with reference to Figure 1 that the depth of the slot 36 is such that the two legs 19 and 20 are pulled inwardly from their straight line position. Without this restriction they would normally assume a straight line position due to the tension exerted on them by the tensioning spring 24. When the leg 19 expands due to an increase in its temperature, the tension therein is released with the result that the tension in the leg 20 will cause this leg to move towards its straight line position, thereby moving the actuating rod 34 and leg 19 to the left. This principle of operation is exactly the same as that disclosed in the copending application of Willis H. Gille, Serial No. 401,205 referred to in the objects of this invention.

Bracket 38 and bracket 39 are both insulatingly carried on the supporting member 10 and are insulated from each other, being mounted by means of screws 40. The bracket 38 adjustably carries a stationary contact 41 and the bracket 39 adjustably carries a stationary contact 42. Each bracket is provided with a terminal screw 43 for connecting the stationary contacts with an external circuit. Bracket 44 is also mounted on the support 10 by means of screws 45 and this bracket carries a movable contact arm 46 by means of a resilient hinge 47. The movable contact arm 46 carries at its free end a pair of movable contacts 48 and 51 which are adapted to alternately engage the two stationary contacts 41 and 42 respectively. The mid portion of this contact arm is provided with an opening 50 through which the actuating rod 34 is adapted to extend. The connection between the actuating rod 34 and the contact arm 46 is by means of a bowed leaf spring 49, one end of which is secured to the contact arm 46 and the other end of which engages a small opening in the end of the actuating rod 34. This spring tends to move the contact arm 46 toward the right (Figure 1) with respect to the rod 34 and thus maintains it against a shoulder, indicated by reference numeral 52, on the rod 34. The purpose of this is to eliminate any lost motion between rod 34 and contact arm 46 upon reversal in movement of the rod 34.

When the two expandable legs 19 and 20 are at substantially the same temperature, they will be in the position shown in Figure 1 and the contact 51 will be in engagement with the stationary contact 41. When heat is applied to the leg 19 it will expand and relieve the tension therein, at which time the tension in the leg 20 will cause this leg to straighten and move the actuating rod 34 toward the left. The shoulder 50 on the actuating rod 34 will now engage contact arm 46 and force the contact 48 into engagement with the stationary contact 42. This occurs after only a slight movement of the leg 20 and after the engagement of the contact 48 with the stationary contact 42 further movement of the actuating rod will be impossible. In order to accommodate a further straightening of the leg 20, the slip friction mountings composed of the elements 28 to 32 have been provided which will now permit the leg 20 to swing its lower end and lever 13 toward the right, as seen in Figure 1, thus further straightening the leg 20.

When the heat is removed from the leg 19, it will rapidly come to the same temperature as the leg 20, in which case the leg 19 will move in a direction toward its straight line position and will pull the actuating rod 34 toward the right.

The rod 34 through the bowed leaf spring 49 will move the contact 51 into engagement with the stationary contact 41. Further movement of the rod will then be resisted by means of this spring 49 but any further tendency of the leg 19 to straighten and return to the position shown in Figure 1 will result in the lever 13 being rotated in a clockwise direction as permitted by the slip friction mountings.

It will be seen therefore that this device is extremely sensitive in that the very first movement of the two legs 19 and 20 due to their differential expansion causes an actuation of the switching mechanism and that any additional movement results in a slippage of the mounting lever 13. Upon a reversal in temperature change the first movement of the legs 19 and 20 will again cause actuation of the switching mechanism and a further movement will be accommodated by the slippage of the lever 13.

A slight modification of the above arrangement is disclosed in Figure 4. In this figure, the lever 13 has been replaced by a roller 55 which is fixed to an axle 56. The axle 56 extends through openings 57 in the opposite side of the channel shaped supporting member 10. This modification is provided with a resilient tensioning plate 24 in the same manner as the modification shown in Figure 1, whereby the two legs 19 and 20 are always under tension and exert an upward force on the roller 55. It will be noted in connection with Figure 6 that the openings 57 are not round but are more or less oval shaped with the result that the axle 56 engages the sides of these openings in two places indicated at 58 and 59. There is, therefore, no tendency of this axle to move laterally as it rotates. Moreover, the sliding friction between the axle 56 and the sides of the opening 57 normally resists rotation of the roller 55 and this rotation takes place only after the actuation of the contact mechanism by the actuating rod 34. This occurs in the same manner as described in connection with Figure 1, and a further description here is not believed necessary.

There is a possibility that after a long period of disuse and after a number of temperature variations this mechanism might possibly get out of step and for this reason a manual reset lever 60 is provided with an up-turned end 61 which engages beneath a lip 62 formed on the supporting member 10. The lever 60 has a bearing surface 63 which engages the center portion of the tension spring 24, so that when the right-hand end of this lever 60 is depressed the spring 24 is bent inwardly and the tension on the two legs 19 and 20 is relieved. At this time, therefore, the ribbon 16 will slip with respect to the roller 55 and equalize the tension in the two legs 19 and 20. When the manual lever 60 is released the two legs 19 and 20 will be under equal tension and the contact arm will be in engagement with the proper stationary contact. The device will then be in a condition to function properly.

Figure 7 shows a further modification of this invention in which the roller 55 is fixed with respect to the supporting member 10. The slip friction in this case is provided between the actuating rod 34 and the contact arm 46. This slip friction comprises an opening in the contact arm 46 through which the actuating arm 34 extends. This opening is provided with an inlet 65 which carries a pair of spring blades 66 and 67 which are biased into engagement with that portion of the actuating rod 34 which extends through the opening in the contact arm 46. The friction be-

tween the blades 66 and 67 in the actuating rod 34 is sufficient for the contact arm 46 to be actuated by means of the rod 34, but after the contacts 51 or 48 have moved into engagement with either of the stationary contacts 41 or 42 respectively, then further differential expansion between the two legs 19 and 20 will be taken care of by the rod 34 slipping with respect to the contact arm 46. Here again, therefore, the switching mechanism will be actuated as a result of the initial differential expansion between the two legs 19 and 20 in each direction, and therefore a device is provided which is extremely sensitive.

It might be explained that the upper ends of the two legs 19 and 20 are mounted in a slightly different manner in Figure 7 than in the modifications shown in Figures 1 and 2. In this case, the ends of these legs are bent into a supporting member 78 and clamped therein by means of a clamping plate 71. This clamping plate is supported by means of two screws 72 which extend loosely through openings in a tensioning plate 74 to provide the proper tension on the two legs 19 and 20.

Figure 8 merely shows the conventional oil burner 75 for producing a flame 76 in the combustion chamber of a furnace, one wall of which is shown in section at 11. The device of my invention may be mounted in a casing 78 and positioned in opening 79 in the wall of the furnace in such a manner that the leg 19 is positioned to absorb radiant heat from the flame 76. Positioned in this manner, it will be seen that the leg 19 protects or shields the leg 20 from direct heat radiations. For this reason, when combustion is present within the furnace the leg 19 will be at a higher temperature than the leg 20 and therefore the leg 19 will be expanded with respect to the leg 20 and the contact arm 46 will be in engagement with the stationary contact 42. Upon disappearance of the flame the two legs 19 and 20 will rapidly come to the same temperature and the parts will return to the position shown in Figures 1, 4 and 7, depending upon which modification is being used.

This invention has been described in connection with an oil burner control system so that it will respond to the radiant heat of combustion, but it will be readily appreciated that there are many other adaptations. For example, an electrical heating winding may be wrapped directly about the leg 19 in order that the switch contact 42 might be engaged upon the application of heat to the leg 19 and the contact 41 engaged when no heat is applied thereto.

Many other changes and modifications in this invention will doubtless occur to those who are skilled in the art, and I therefore wish it to be understood that I am to be limited only by the scope of the appended claims and not by the specific embodiments disclosed.

I claim as my invention:

1. In a device of the character described, an elongated heat expandable member bent double to form a pair of substantially parallel expandable legs, means placing said legs under tension thereby tending to make them assume straight line positions, a movably mounted actuating rod having means acting between said two legs and forcing them out of their straight line position whereby said actuating rod will be moved upon a differential expansion of said legs, and a rotatably mounted arm actuated by said rod for operating a control device.

2. In a device of the character described, an

elongated heat expandable member bent double to form a pair of substantially parallel expandable legs, means placing said legs under tension thereby tending to make them assume straight line positions, a movably mounted actuating rod having means acting between said two legs and forcing them out of their straight line position whereby said actuating rod will be moved upon a differential expansion of said legs, a movable contact arm, stationary contact means cooperable therewith, and impositive driving means between said actuating rod and said contact arm whereby relative movement may take place between said actuating rod and contact arm after said stationary contact means has been engaged.

3. In a device of the character described, an elongated heat expandable member bent double to form a pair of substantially parallel expandable legs, means placing said legs under tension whereby they tend to assume straight line positions, a movably mounted actuating rod having means acting between said two legs and forcing them out of their straight line position whereby said actuating rod will be moved upon a differential expansion of said legs, stationary contact means, a movable contact moved by said actuating rod into engagement with said stationary contact means, and slip friction means providing for continued movement of said other leg toward straight line position after said movable contact has engaged said stationary contact means.

4. In a device of the character described, a thin metallic ribbon bent double to form a pair of substantially parallel expandable legs, means placing said legs under tension whereby they tend to assume straight line positions, a movably mounted actuating rod having a slightly enlarged head at one end, a slot in said head through which both legs of said double ribbon pass, said head and ribbon having interfitting portions by means of which said head is supported by said ribbon, the depth of said slot being such that said legs are pulled inwardly from their straight line positions whereby said actuating rod will be moved upon a differential expansion of said legs, and a control device actuated by said rod.

5. In a device of the character described, a thin metallic ribbon bent double to form a pair of substantially parallel expandable legs, means placing said legs under tension whereby they tend to assume straight line positions, a movably mounted actuating rod having a slightly enlarged head at one end, a slot in said head through which both legs of said double ribbon pass, said head and ribbon having interfitting portions by means of which said head is supported by said ribbon, the depth of said slot being such that said legs are pulled inwardly from their straight line positions whereby said actuating rod will be moved upon a differential expansion of said legs, a movable contact arm, stationary contact means cooperable therewith, and impositive driving means between said actuating rod and said contact arm whereby relative movement may take place between said actuating rod and contact arm after said stationary contact means has been engaged.

6. In a device of the character described, a thin metallic ribbon bent double to form a pair of substantially parallel expandable legs, means placing said legs under tension whereby they tend to assume straight line positions, a movably mounted actuating rod having a slightly enlarged head at one end, a slot in said head through which both legs of said double ribbon pass, said head and

ribbon having interfitting portions by means of which said head is supported by said ribbon, the depth of said slot being such that said legs are pulled inwardly from their straight line positions whereby said actuating rod will be moved upon a differential expansion of said legs, a movable contact arm, stationary contact means cooperable therewith, and slip friction means providing for continued movement of said other leg toward its straight line position after said contact arm has been stopped by said stationary contact means.

7. In a device of the character described, a supporting member, a mounting member rotatably mounted on said supporting member, a double ribbon temperature responsive device comprising a pair of substantially parallel expandable legs mounted at one end on said mounting member, a resilient member supporting the other end of said legs and maintaining them under tension whereby they tend to assume a straight line position, means carried by said legs and holding them out of their straight line position whereby said legs will move laterally upon a differential expansion thereof, a control device movable a limited distance by said legs, and slip friction means between said rotatable mounting member and said supporting member which provides for said legs first actuating said control device through its limited movement and then rotates about said supporting member to permit said other leg to continue to move toward its straight line position as said one leg continues to expand.

8. In a device of the character described, a supporting member, a U shaped mounting member rotatably mounted at the bend of the U on said supporting member, a double ribbon temperature responsive device comprising a pair of substantially parallel expandable legs mounted at one end on said mounting member, a resilient member supporting the other end of said legs and maintaining them under tension whereby they tend to assume a straight line position, means carried by said legs and holding them out of their straight line position whereby said legs will move laterally upon a differential expansion thereof, a control device movable a limited distance by said legs, and slip friction means located between the legs of the U of said U shaped mounting member and said supporting member which provides for said legs first actuating said control device through its limited movement and then rotates about said supporting member to permit said other leg to continue to move toward its straight line position as said one leg continues to expand.

9. In a device of the character described, a supporting member, a roller frictionally journaled in said supporting member, a thin metallic ribbon bent double across said roller to form a pair of substantially parallel expandable legs, resilient means supporting the ends of said legs and placing them under tension thereby tending to make them assume straight line positions, means carried by said legs holding them out of their straight line positions whereby said legs move laterally upon a differential expansion thereof, and a control device movable a limited distance by said legs, said roller slipping with respect to said supporting member to permit further movement of said other leg after said control device has been moved to a limit position.

10. In a device of the character described, a supporting member, a roller frictionally journaled in said supporting member, a thin metallic

ribbon bent double across said roller to form a pair of substantially parallel expandable legs, resilient means supporting the ends of said legs and placing them under tension thereby tending to make them assume straight line positions, means carried by said legs holding them out of their straight line positions whereby said legs move laterally upon a differential expansion thereof, a control device movable a limited distance by said legs, said roller slipping with respect to said supporting member to permit further movement of said other leg after said control device has been moved to a limit position, and means for manually relieving the tension in said legs whereby said ribbon may slip with respect to said roller to equalize the tension in said legs.

11. In a device of the character described, a supporting member, a mounting member having a rounded mounting surface carried by said supporting member, a thin metallic ribbon bent double across said mounting member and engaging said rounded surface, said ribbon forming two substantially parallel expandable legs, a tensioning plate carried by said supporting member, means connecting the ends of said ribbon to said tensioning plate whereby it maintains said legs under tension, means carried by said legs holding them out of their straight line positions whereby said legs move laterally upon a differential expansion thereof, a control device actuated by said legs, and a lever rotatably mounted on said supporting member and engaging said tensioning plate whereby said plate may be manually depressed to relieve the tension in said two legs and permit said ribbon to slide on the mounting member and equalize the tension in said legs.

12. In a device of the character described, a double ribbon temperature responsive device comprising a pair of substantially parallel expandable legs, means maintaining said legs under tension whereby they tend to assume straight line positions, an actuating member, one end of which is carried by said legs, said one end holding said legs out of their straight line positions, a movable contact arm, stationary contact means engageable by said arm, a slip friction connection between said actuating member and said arm, and means for heating one of said legs whereby it expands and said other leg moves toward its straight line position and moves said actuating member, said slip friction connection permitting further movement of said other leg after said contact arm has engaged said stationary contact means.

13. In a device of the character described, a double ribbon temperature responsive device comprising a pair of substantially parallel expandable legs, means maintaining said legs under tension whereby they tend to assume straight line positions, an actuating member, one end of which is carried by said legs, said one end holding said legs out of their straight line positions, a rotatably mounted contact arm, a pair of oppositely disposed stationary contacts alternately engageable by said contact arm, an opening in said arm through which the other end of said actuating member extends, a pair of resilient fingers carried by said contact arm and frictionally engaging said actuating member to form a slip friction connection, and means for heating one of said legs whereby it expands and said other leg moves toward its straight line position and moves said actuating member, said slip friction connection permitting further movement of said

other leg after said contact arm has engaged said stationary contact means.

14. In a device of the character described comprising in combination, an elongated flexible metallic member bent double to form a pair of heat expandable legs, means supporting said legs and placing them under tension whereby they tend to assume straight line positions, an actuating member having means acting on at least one of said legs forcing it out of its straight line position, whereby upon a differential expansion of said legs the tension in said one leg changes causing said leg to move said actuating member, a control device, and a slip friction connection between said actuating member and said control device.

15. In a device of the character described comprising in combination, an elongated flexible me-

tallic member bent double to form a pair of heat expandable legs, means supporting said legs and placing them under tension whereby they tend to assume straight line positions, an actuating member having means acting on at least one of said legs forcing it out of its straight line position, whereby upon a differential expansion of said legs the tension in said one leg changes causing said leg to move said actuating member, 5 stationary contact means, a rotatably mounted contact arm, a movable contact carried thereby for cooperation with said stationary contact means, and means connecting said actuating member and said contact arm including a slip 10 friction device whereby additional movement of said one leg is permitted after said movable contact has been actuated.

BENJAMIN CYR.
